UNITED STATES PATENT OFFICE

2,088,720

HYDRESPIRATOR

Louis Poliniak, Shamokin, Pa.

Application March 4, 1937, Serial No. 129,034

5 Claims. (Cl. 128—146)

This invention aims to provide a simple but efficient means for purifying the air of dust, fumes and foreign matter which, if drawn into the human lungs, produces discomfort or disease.

5 The invention aims to provide novel means for leading the air downwardly through a body of water, before the air is breathed, novel means being provided for exhausting the air which has passed through the lungs of the operator. Another object of the invention is to improve the means whereby air is admitted into the water or other liquid, to improve the means whereby the air which has been breathed is exhausted, and to improve the conduit whereby the air moves 10 back and forth, between the tank and the mouth of the wearer.

It is within the province of the disclosure to improve generally and to enhance the utility of devices of that type to which the present invention appertains.

20 With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

25 In the accompanying drawings:

Fig. 1 shows in perspective, a device constructed in accordance with the invention, mounted on the body of a wearer;

Fig. 2 is an elevation of the conduit and the mouth piece, parts being broken away and parts being shown in section;

Fig. 3 is a section on the line 3—3 of Fig. 2;

Fig. 4 is a longitudinal section of the tank and parts which support it on the body of the user;

Fig. 5 is a section on the line 5—5 of Fig. 4;

If desired, the device may include a pouch or carrier 1, the rear wall of which is supplied with an upstanding tab 2 having eyes 3, through which passes a belt 4, adapted to hold the mechanism hereinafter described on the chest of the wearer, as shown in Fig. 1: although some support different from the pouch may be resorted to, and it is by no means necessary that the pouch be located in the precise position depicted in Fig. 1 45 of the drawings.

An elongated, round-ended tank 5 is mounted removably in the pouch 1 and is adapted to contain a quantity of water or other liquid, indicated at 10. The liquid 10 does not completely 50 fill the tank 5.

Adjacent to one end, the tank 5 is provided with a first nipple 6. A yieldable washer 7 rests on the top of the tank 5, within the nipple 6, and on top of the washer 7 is disposed an annular outstanding flange 8 at the upper end of a 5 substantial vertical air inlet tube 9, the air inlet tube extending downwardly through the top of the tank 5, into the liquid 10 in the tank, as shown in Fig. 4. The air inlet tube 9 is supplied in its bottom, and in its sides, below the level of 10 the liquid 10, with perforations 11.

The numeral 12 marks a cap having side inlet openings 14, the cap including a reduced neck 15 provided at its lower end with an annular, inwardly projecting flange 16. The neck 15 of the 15 cap 12 is threaded downwardly in the nipple 6, until the flange or foot 16 presses tightly against the outstanding flange 8 of the air inlet tube 9, the flange 8, in turn, being pressed tightly against the washer 7, and a water tight joint thus being 20 effected.

The numeral 17 designates a second nipple, provided at its lower end with an outstanding annular flange or foot 29, which is secured to the top of the tank 5, the second nipple 17 being located intermediate the ends of the tank 5. The upper wall of the second nipple 17 carries an upstanding, reduced neck 18. A compressible washer 19 is disposed about the neck 18 and rests on the upper wall of the nipple 17.

A ring 20 is threaded on the nipple 17 and includes an outstanding flange or foot 21, at its lower edge, pressing on the washer 19 and affording a tight joint. A hinge plate 22 is secured to the outer surface of the ring 20 and is pivotally connected at 23 with a hinge plate 24 extended across the upper end of the ring 20, the hinge plate 24 being enclosed in a casing 25 of rubber or other resilient material. It will be seen that the hinge plates 22 and 24, together with the casing 25, constitute an outwardly opening and inwardly closing check valve of the flap type.

A cap 26 is threaded on the nipple 17 and is provided at its lower end with an outstanding foot or flange 27 which exerts pressure on a resilient washer 28, resting on the foot 29 of the nipple 17 and surrounding the nipple, an air tight joint being afforded. The cap 26 is supplied near its upper end with side inlet perforations 30.

A third nipple 31 is mounted on the top of the tank 5, adjacent to that end of the tank which is remote from the air inlet tube 9. The lower end of a flexible tubular conduit 33 is threaded on the nipple 31, as shown in Fig. 4. Intermediate 55

its ends, the conduit 33 has an enlargement 34 of bulb-like form, affording increased radiating surface and tending to condense the moisture out of the air which is drawn upwardly through the 5 conduit 33.

The upper end of the conduit 33 is threaded on the curved neck 35 of a mouth piece 36, the neck and the mouth piece preferably being made of hard material. The mouth piece 36 is so 10 shaped that it will fit closely about the mouth of the wearer, and in the upper edge of the mouth piece 36 there is a notch 37, adapted to receive the nose of the wearer. The edge of the mouth piece 36 is shod with a soft facing 38 of rubber 15 or the like, enabling the mouth piece to fit closely against the wearer's face. Any suitable means may be supplied for holding the mouth piece 36 in place. For instance, the neck 35 may be surrounded by a yoke ring 39, engaging the mouth piece 36, as shown in Fig. 3, and a band or straps 40 may be connected to the yoke ring 39, the band or straps passing around behind the wearer's head, as shown in Fig. 1. Any equivalent for the ring 39 and the band or straps 40 may be 20 provided.

In practical operation, when the wearer draws air into his lungs, the air enters the cap 12 through the openings 14 and passes downwardly through the tube 9, the air entering the water or other liquid 10 through the perforations 11 in the lower end of the tube 9. The air rises through the liquid 10, and as the air moves upwardly through the liquid, it is purged of impurities, such as dust or the like, these impurities remaining in the liquid 10. The air moves upwardly through the conduit 33 and the mouth piece 36 and is taken into the wearer's lungs. When the wearer inhales, the check valve shown at 22—24—25 is closed by gravity, aided by suction.

40 When the wearer exhales, the air is forced downwardly through the mouth piece 36 and through the tube 33, the air entering the tank 5 above the level of the liquid 10. The air passes upwardly through the nipple 17 and through the ring 20, the flap valve 22—24—25 opening to 45 permit an exhaust of the air, the air leaving the cap 26 by way of the perforations 30.

The device is simple in construction, but it is so made that it may be mounted readily on the body of a workman, the air which he breathes being washed clear of impurities, and the diseases which result from breathing dust or other foreign matter being avoided. Practically the only part of the device which is subject to appreciable wear is the check valve 24—22—25, and this check 55 valve may be renewed by threading the ring 20 off the neck 18 of the nipple 17 and substituting a new ring and check valve.

Having thus described the invention, what is claimed is:

60 1. In a device of the class described, a tank adapted to contain liquid, an air inlet tube connected to the upper portion of the tank and opening at its lower end within the liquid in the tank, an outwardly opening check valve carried by the upper portion of the tank and located above the liquid in the tank, a conduit connected at its lower end with the tank, above the liquid in the tank, a mouth piece mounted on the upper end of the conduit, means for securing the mouth piece to the head of a wearer, and means for carrying the tank on the body of a wearer.

70 2. In a device of the class described, a tank

adapted to contain liquid, a nipple on the upper portion of the tank, a washer within the nipple and resting on the top of the tank, an air inlet tube opening at its lower end within the liquid in the tank and provided at its upper end with an annular outstanding flange resting on the washer, a cap having an air inlet, the cap being threaded into the nipple and bearing at its lower end against the flange of the inlet tube, to press said flange against the washer and make 10 a tight joint, an outwardly opening check valve carried by the upper portion of the tank and located above the liquid in the tank, a conduit connected at its lower end with the tank, above the liquid in the tank, a mouth piece mounted 15 on the upper end of the conduit, means for securing the mouth piece to the head of a wearer, and means for carrying the tank on the body of a wearer.

3. In a device of the class described, a tank 20 adapted to contain liquid, an air inlet tube connected to the upper portion of the tank and opening at its lower end within the liquid in the tank, a nipple mounted on the top of the tank and provided with an upper wall carrying 25 a reduced neck, a ring threaded on the neck, a washer interposed between the lower end of the ring and the upper wall of the nipple, an outwardly opening check valve carried by the ring, a cap threaded on the nipple and housing the 30 neck and the check valve, the cap being provided with an air inlet opening, the check valve being located above the liquid in the tank, a conduit connected at its lower end with the tank, above the liquid in the tank, a mouth piece 35 mounted on the upper end of the conduit, means for securing the mouth piece to the head of a wearer, and means for carrying the tank on the body of a wearer.

4. In a device of the class described, a tank 40 adapted to contain liquid, an air inlet tube connected to the upper portion of the tank and opening at its lower end within the liquid in the tank, a nipple mounted on the upper portion of the tank and provided with an upper wall 45 carrying a reduced neck, a ring threaded on the neck, an outwardly opening check valve carried by the ring, a cap threaded on the nipple and enclosing the neck and the check valve, the cap being provided with an air inlet opening, a conduit connected at its lower end with the tank, above the liquid in the tank, a mouth piece 50 mounted on the upper end of the conduit, means for securing the mouth piece to the head of the wearer, and means for carrying the tank on the body of a wearer.

5. In a device of the class described, a tank 55 adapted to contain liquid, an air inlet tube connected to the upper portion of the tank and opening at its lower end within the liquid in the tank, an outwardly opening check valve carried by the upper portion of the tank and located above the liquid in the tank, a conduit connected at its lower end with the tank, above the liquid in the tank, a conduit being provided intermediate its ends with an enlargement affording 60 increased radiating surface and constituting a condenser for moisture, a mouth piece mounted on the upper end of the conduit, means for securing the mouth piece to the head of a wearer, and means for carrying the tank on the body 65 of a wearer.

LOUIS POLINIAK.
